RAILWAY DRAFT RIGGING

Original Filed May 16, 1929

UNITED STATES PATENT OFFICE

JOHN F. O'CONNOR, OF CHICAGO, ILLINOIS, ASSIGNOR TO W. H. MINER, INC., OF CHICAGO,
ILLINOIS, A CORPORATION OF DELAWARE

RAILWAY DRAFT RIGGING

Application filed May 16, 1929, Serial No. 363,636. Renewed January 7, 1932.

This invention relates to improvements in railway draft riggings.

One object of the invention is to provide a draft rigging for railway cars wherein greater shock absorbing capacity is obtained in buff than in draft by means of a plurality of shock absorbing mechanism, all of which are actuated in buff and part only thereof actuated in draft.

Another object of the invention is to provide a railway draft rigging having longer travel in buff than in draft action to produce higher shock absorbing capacity during the former action, wherein a plurality of shock absorbing mechanisms are employed, all of which are compressed in buff and certain of which only are compressed in draft, the last named mechanisms being compressed in tandem during the draft action.

A further object of the invention is to provide a railway draft rigging including tandem arranged shock absorbing means and additional shock absorbing mechanism, together with means for actuating both of the tandem shock absorbing means and the additional shock absorbing mechanism in buff and actuating only the tandem shock absorbing means in draft, wherein the members of the tandem shock absorbing means are disposed respectively in front and in back of the body bolster at the corresponding end of the car, and the body bolster serves as stop means for both members of the tandem shock absorbing means.

Yet another object of the invention is to provide a railway draft rigging having longer travel in buff than in draft, including a tandem arranged spring shock absorbing means; a friction shock absorbing mechanism; a coupler means, wherein the members of the spring shock absorbing means are actuated in tandem during a draft action of the coupler and both the spring shock absorbing means and the friction shock absorbing mechanism are actuated in a buffing action of

the coupler, one of the members of the spring shock absorbing means being actuated in advance of the other during the first part of the buffing action, and the latter and the friction shock absorbing mechanism being actuated in tandem during the latter part of the buffing action.

A more specific object of the invention is to provide a draft rigging for railway cars including fixed draft sills, a combined stop and bolster filler casting between the sills; coupler means; spring shock absorbing members disposed respectively in front and in back of the stop casting; front and rear followers cooperating with each spring shock absorbing mechanism, the front followers being held against outward movement in draft and the rear followers being held against rearward movement in buff; side members connected to the coupler means for actuating the rear followers in draft to compress the shock absorbing members in tandem; friction shock absorbing means interposed between the coupler shank and the front follower of the shock absorbing member in front of the stop casting, adapted to be actuated by inward movement of said coupler means in buff and to move said follower inwardly to compress the cooperating spring shock absorbing member, inward movement of said front follower being limited by stop means on the draft sills after a predetermined compression of said spring shock absorbing member, whereby the friction shock absorbing means is compressed between the coupler and said follower during the remainder of the buffing stroke, the connection between the coupler and the side members providing a certain amount of lost motion during the buffing stroke to allow relative movement between the coupler and side members during the first part of the buffing stroke and permit inward movement of the side members in unison with the coupler during the last part of the buffing

80

85

90

95

stroke to effect inward movement of the outer follower of the shock absorbing spring means disposed in back of the bolster to compress the same.

5 Other objects of the invention will more clearly appear from the description and claims hereinafter following.

In the drawing, forming a part of this specification, Figure 1 is a horizontal, longitudinal sectional view through the under-frame structure of a railway car showing my improvements in connection therewith. Figure 2 is a longitudinal, vertical, sectional view corresponding substantially to the line 10 2-2 of Figure 1. Figure 3 is a front end elevational view of the structure shown in Figure 1 with the coupler omitted. And Figure 4 is a transverse, vertical, sectional view corresponding substantially to the line 15 4-4 of Figure 2.

In said drawing, 10-10 indicate the usual channel-shaped center or draft sills of the railway car underframe and 12 the body bolster of the car. An end sill 13 of usual 25 form is secured to the outer ends of the sills 10, the same being provided with the usual striking casting member 14, having a carry iron section 15.

In carrying out my invention, I provide 30 the body bolster 12 with a combined stop and filler casting 16 which is secured to the same and has a vertical pin-receiving opening 117 which accommodates the usual center pin member of the car. As most clearly shown 35 in Figure 1, the side faces of the stop casting 16 are spaced an appreciable distance from the corresponding sills 10 for a purpose hereinafter pointed out. The front and rear faces 17-17 of the casting 16 serve as stop 40 means for followers of certain of the shock absorbing means of the draft rigging as hereinafter pointed out.

The fixed draft sills 10 are provided with 45 key-receiving openings or slots 18, 19 and 20, the slots of the opposed sills being in transverse alinement. Each of the slots is reinforced by a cheek plate secured to the outer side of the corresponding sill and having inwardly and outwardly projecting flanges surrounding the key-receiving opening thereof, the inner flanges being seated in a suitable opening in the sill. As clearly shown in 50 Figures 1 and 2, the openings 19 and 20 are of substantially the same length while the opening 18 is appreciably longer than the openings 19 and 20.

The coupler member of the railway car is 55 designated by 21 and is of the usual standard form. A pair of longitudinally extending side members 22-22 are connected to the coupler. The members 22 are movable lengthwise of the car and are slideable in the openings provided between the casting 16 and the sills 10. Each of the members 22 is provided with a key receiving slot or opening 23

at the forward end thereof, a second key receiving opening or slot 24 between the ends of the same and a third key receiving opening or slot 25 at the rear end thereof. As clearly shown in the drawings, the key receiving openings 23-23, 24-24 and 25-25 of the two members 22 are in transverse alinement respectively. Each of the key receiving openings of the members 22 is reinforced by inwardly projecting flanges surrounding each 75 opening. The openings 23, 24 and 25 are preferably all of the same length.

The coupler is connected to the side members 22 by a transverse coupler key 26 extending through an opening 27 in the coupler shank and having its opposite ends disposed in the openings 23 of the members 22 and having the outer extremities thereof working in the openings 18 of the draft sills. As shown in Figure 1, the front edge of the key 26 is normally in engagement with the front end walls of the openings 23 of the member 22 and has said front edge spaced slightly from the front end wall of the opening 27 in the coupler shank. At the forward end, each member 22 is provided with top and bottom inwardly projecting horizontal flanges 28-28 which extend above and below the coupler shank. As shown most clearly in Figure 3, the bottom flanges 28 are upwardly offset so as to provide shelf or ledge means for supporting the coupler shank. It is further pointed out that the side members 22 normally project outwardly beyond the end sill 13 of the car as clearly shown in Figure 1.

Spring shock absorbing means is disposed in front and in back of the bolster 12, the spring shock absorbing member in front of the bolster being indicated by 29 and the spring shock absorbing member to the rear of the bolster being indicated by 30. Each spring shock absorbing member preferably comprises an inner light coil and a relatively heavier outer coil. A plate-like follower member 31 is interposed between each shock absorbing member and the stop casting 16 of the bolster. The followers 31 normally bear on the front and rear abutment faces 17 of the casting 16 and have shouldered engagement with the side members 22. To provide this shouldered engagement, each side member is thickened as indicated at 32, said thickened portion providing front and rear transverse abutment or stop shoulders 33-33 which engage with the side portions of the follower members 31. Follower means is also provided for the opposite end of each spring shock absorbing member, said follower means being preferably in the form of a follower block 39. The follower block 39 of the spring shock absorbing member 29 disposed in front of the body bolster forms a front follower for said shock absorbing member and the follower 39, cooperating with the spring shock absorbing member 30 to the

125

130

135

rear of the bolster 12, forms the rear follower for said shock absorbing member. In this connection, it is pointed out that the follower 31 associated with the shock absorbing member 29 in front of the bolster forms the rear follower thereof while the follower 31 associated with the shock absorbing member 30 to the rear of the bolster 12 forms the front follower thereof. The followers 39 are of similar design and each is provided with a transverse key receiving opening 40 through which a key 41 extends. The key 41 closely fits the opening 40 so that the key and follower move in unison. The opposite ends of each key 41 work in the corresponding slots of the side members 22 and the draft sills 10. The key 41 of the follower 39, which cooperates with the spring shock absorbing member in front of the bolster 12, has the front edge thereof normally in engagement with the front end walls of the slots or openings 19 and 24 of the fixed sills 10 and the movable side members 22 respectively, while the key 41 of the other follower 39 has the rear edge thereof in engagement with the rear end walls of the slots 20 and 25 of the fixed sills and side members 22 respectively. In order to maintain the coils of the spring members 30 in proper alignment and in assembled relation with the followers, each follower 31 and 39 is provided with an inwardly projecting boss engaging within the corresponding end of the inner coil of the corresponding spring resistance member.

A friction shock absorbing mechanism 42 is interposed between the inner end of the coupler shank and the follower 39 which is in front of the bolster 12. The shock absorbing mechanism 42 may be of any well known type and is therefore not shown in detail. This mechanism is of the type which comprises a friction shell member and cooperating friction means in the form of friction shoes and a wedge block, the same being spring resisted by spring means disposed within the shell. The friction shoes of such a friction shock absorbing mechanism are indicated by 43-43 and the wedge block by 44. A follower member in the form of a relatively heavy plate 45 is interposed between the wedge member 44 of the friction shock absorbing mechanism and the butt end of the coupler shank. The friction shell of the shock absorbing mechanism preferably bears directly on the front face of the follower 39. In order to support the friction shell in operative position, a saddle plate 46 is employed which is detachably secured to the bottom flanges of the sills 10. The follower 45 is provided with the usual centering projection at the forward side thereof, which engages within a suitable opening provided in the butt end of the coupler shank.

As shown in the drawing, the three keys 35 of the railway draft rigging are all of the

same width and the corresponding key openings or slots of the movable side members 22 are also all preferably of the same length so that all of the keys have the same amount of movement in the slots of the side members. The slots 18 of the draft sills are of such a length as to permit the necessary forward movement of the key 26 in draft and also the necessary movement of the same in buff to allow for full compression of the shock absorbing mechanisms of the railway draft rigging.

The operation of my improved railway draft rigging, assuming an inward or buffing movement applied to the coupler 21 is as follows: The coupler, while being forced inwardly, will carry the follower 45 therewith, forcing the friction shock absorbing mechanism 42 rearwardly as a unit, the friction shock absorbing mechanism being of greater capacity than the spring shock absorbing member 29 in front of the bolster 12 so that compression of such spring shock absorbing member will be effected during the first part of the buffing action without compression of the friction shock absorbing mechanism. The spring shock absorbing member 29 in front of the bolster 12 will be compressed by inward movement of the follower 39, the rear follower 31 of said shock absorbing member being held stationary by engagement with the stop casting 16. Compression of the spring member 29 referred to will continue until the key 41 of the front follower 39 thereof engages the inner end walls of the slots 19 of the sills 10, whereupon said follower 39 will be held stationary. As will be evident, the friction shock absorbing mechanism 42 will thereafter be compressed between the coupler and the follower 39 during the remainder of the buffing stroke of the gear. As the coupler 21 moves inwardly, the key 26 will be carried therewith until the same engages the rear end walls of the slots 23 of the side members 22. When the coupler has moved inwardly a sufficient distance to engage the key 26 with the rear end walls of said slots and to take up the clearance between the front edge of the key and the front end wall of the opening 27 in the coupler shank, the key will be forced rearwardly in unison with the coupler, thus carrying the movable side members 22 therewith. Upon rearward movement of the side members 22, the front follower 31 of the shock absorbing member 30 to the rear of the bolster 12 will be forced rearwardly by the shoulders 33 of the members 22, thereby compressing the spring member 30 between the follower 17 and the corresponding rear follower 39 which is held stationary by its key 41 engaging the inner end walls of the slots 20 of the sills 10. Compression of the spring member 30, last referred to, will be limited by the compression of the friction shock absorbing

100
105
110
115
120
125
130

120

mechanism when the follower 45 thereof engages the front end of the friction shell. At this time, the front end walls of the slots 24 and 25 of the side members will also engage 5 the front edges of the keys 41 of the followers 39 thereby arresting movement of the side members 22 simultaneously with engagement of the follower 45 with the friction shell of the friction shock absorbing mechanism.

10 As will be evident, during the buffing action described, the spring shock absorbing member 29 in front of the bolster 12 will be compressed during the first part of the buffing action; thereafter the friction shock absorbing 15 mechanism 42 will be compressed to a slight degree due to the relative movement between the key 26 and the coupler due to the clearance between the key and the slot 27 of the coupler shank, and during the re- 20 mainder of the buffing action the friction shock absorbing mechanism 42 and the spring shock absorbing member 30 to the rear of the bolster 12 will be compressed simultaneously and in tandem.

25 When an outward pull or draft action is applied to the coupler 21, the side members 22 will be pulled forwardly therewith by the connecting key 26, thereby compressing both spring shock absorbing members 29 and 30 30 in tandem. The spring shock absorbing member 29 in front of the bolster 12 is compressed between the corresponding follower 31 and the follower 39, the latter being held stationary by the key 41 while the former is forced forwardly by the stop shoulders 33 35 of the members 22. The spring shock absorbing member 30 to the rear of the bolster 12 is compressed between the corresponding followers 39 and 31, the follower 31 being held in fixed position by engagement with the stop casting 16 while the follower 39 is pulled forwardly by the side members 22. Compression of the two spring shock absorbing members 29 and 30 is finally limited by 40 the keys 41, the inner end walls of the slots 24 of the members 22 engaging the key 41 of the shock absorbing member 39 and the key 41 of the shock absorbing member 30 engaging the front end walls of the slots 20 of the 45 sills 10. Inasmuch as the friction shock absorbing mechanism 42 is not connected to the coupler so as to move therewith in draft, and the inner end of the friction shell thereof engages the relatively fixed follower 39, the 50 friction shock absorbing mechanism will not be compressed during a draft action. The draft action is thus limited to the compression stroke of the spring shock absorbing members 29 and 30, which are compressed 55 in tandem. The movement of the coupler shank in buff is equal to the combined compression strokes of the spring shock absorbing member 29 and the friction shock absorbing mechanism, as these are actuated in sequence. As will be evident, the buffing stroke

of the railway draft rigging thus exceeds the draft stroke thereof to the extent of the compression stroke of the friction shock absorbing mechanism.

I have herein shown and described what I 70 now consider the preferred manner of carrying out my invention, but the same is merely illustrative and I contemplate all changes and modifications that come within the scope of the claims appended hereto. 75

I claim:

1. In a railway draft rigging, the combination with a shock absorbing mechanism; of shock absorbing means; a shock absorbing member; and means for operatively connecting the coupler means with said shock absorbing mechanism, said shock absorbing means and said shock absorbing member, for actuating the shock absorbing means in both buff and draft, actuating the shock absorbing mechanism in buff only, and actuating said shock absorbing member in draft, said last named member being actuated through said mechanism during the first part of the buffing stroke, said shock absorbing means being actuated in tandem respectively with said shock absorbing mechanism and said shock absorbing member during a buffing and during a draft action of said rigging. 90

2. In a railway draft rigging, the combination with a coupler; of a shock absorbing mechanism; shock absorbing means; a shock absorbing member; and means for actuating said shock absorbing member, said shock absorbing means and said shock absorbing mechanism through the movement of the coupler, said actuating means being operative to actuate the shock absorbing member through the shock absorbing mechanism during the first part of a buffing action, and actuate both the shock absorbing mechanism and the shock absorbing means in tandem during the latter part of the buffing action, said actuating means being operative in draft to actuate only the shock absorbing means 100 and shock absorbing member, said means and member being actuated in tandem. 105

3. In a railway draft rigging, the combination with a friction shock absorbing mechanism; of a spring shock absorbing member actuated through said mechanism in buff; spring shock absorbing means; a coupler; and means operative by the coupler for transmitting buffing and draft forces, said means actuating the spring shock absorbing means 115 in both buff and draft, the spring shock absorbing member in draft, and the friction shock absorbing means in buff only. 120

4. In a draft rigging for railway cars, the combination with draft sills; of a body bolster; a coupler; shock absorbing means in front and in back of the bolster; a shock absorbing mechanism interposed between the coupler shank and the shock absorbing means in front of the bolster, said shock absorbing 125 means

mechanism being of greater capacity than the adjacent shock absorbing means and movable inwardly by the coupler during the first part of the buffing action to compress the adjacent shock absorbing means; said shock absorbing mechanism being compressed by inward movement of the coupler during the latter part of the buffing action; and means operatively connected to the coupler for compressing the shock absorbing means in back of the bolster in tandem with said shock absorbing mechanism, said connecting means being operatively connected with said shock absorbing means to actuate the same in tandem during draft movement of the coupler.

5. In a draft rigging for railway cars, the combination with fixed draft sills; of a combined stop and bolster filler casting between said sills; shock absorbing means in front and in back of said stop casting and cooperating therewith; a coupler; a shock absorbing mechanism interposed between the coupler shank and the shock absorbing means in front of the bolster; and means operatively connected to the coupler for actuating both of said shock absorbing means in draft while said shock absorbing mechanism is idle, and actuating one only of said shock absorbing means in buff.

6. In a draft rigging for railway cars, the combination with fixed draft sills on the car; of a body bolster; shock absorbing means in front and in back of the bolster; front and rear followers cooperating with each shock absorbing means; means for holding the front followers against forward movement and said rear followers against rearward movement; a coupler; a shock absorbing mechanism interposed between the coupler shank and the front follower of the shock absorbing means in front of the bolster; said shock absorbing mechanism and last named shock absorbing means being actuated by inward movement of the coupler; means connecting the coupler with the rear followers of both of the shock absorbing means for actuating the same in draft to effect compression of both of said shock absorbing means in tandem; and cooperating means on said connecting means and the front followers of the shock absorbing means in back of the bolster to actuate said follower and compress said last named shock absorbing means in tandem with the shock absorbing mechanism during a buffing movement of the coupler.

7. In a draft rigging for railway cars, the combination with fixed draft sills on the car; of a combined stop and bolster filler casting between the sills; a coupler; longitudinally extending side members connected to the coupler; shock absorbing means in front and in back of the stop casting; a rear and a front follower interposed between the stop casting and said shock absorbing means respectively, said followers having shouldered engage-

ment with the side members whereby said front follower is actuated in draft and said rear follower is actuated in buff; a rear follower cooperating with the shock absorbing means in back of the bolster, said follower being held against rearward movement and operatively connected to the side members to be actuated thereby in draft; a front follower cooperating with the shock absorbing means in front of the stop casting, said follower being held against forward movement; and shock absorbing mechanism interposed between said last named follower and the butt end of the coupler shank, said shock absorbing mechanism being forced rearwardly in buff to actuate said follower.

8. In a draft rigging for railway cars, the combination with fixed draft sills on the car; of a combined stop and bolster filler casting between the sills; a coupler, longitudinally extending side members connected to the coupler; shock absorbing means in front and in back of the stop casting; a rear and a front follower interposed between the stop casting and said shock absorbing means respectively, said followers having shouldered engagement with the side members whereby said front follower is actuated in draft and said rear follower is actuated in buff; a rear follower cooperating with the shock absorbing means in back of the bolster, said follower being held against rearward movement and operatively connected to the side members to be actuated thereby in draft; a front follower cooperating with the shock absorbing mechanism in front of the stop casting, said follower being held against forward movement; stop means for limiting rearward movement of said follower to less than the full compression stroke of the mechanism; and shock absorbing mechanism interposed between said last named follower and the butt end of the coupler shank, said shock absorbing mechanism being forced rearwardly in buff to actuate said follower and being compressed between the coupler shank and said follower when the latter is arrested by said stop means.

9. In a draft rigging for railway cars, the combination with a couple; of a pair of shock absorbing members; a shock absorbing mechanism actuated in buff only by said coupler, one of said shock absorbing members being actuated through said shock absorbing mechanism and in advance of the same in buff, the movement of the coupler in buff being equal to the combined compression strokes of said shock absorbing mechanism and shock absorbing member; and means connecting the coupler with said shock absorbing members for actuating the same in tandem in draft without actuating said shock absorbing mechanism, and for actuating one of said shock absorbing members in tandem with said shock absorbing mechanism during a buffing action.

10. In a draft rigging for railway cars, the

- combination with draft sills; of a body bolster; a coupler; spring shock absorbing members in front and in back of the bolster; a friction shock absorbing mechanism interposed between the coupler shank and the spring shock absorbing member in front of the bolster, said friction shock absorbing mechanism being of greater capacity than the adjacent spring shock absorbing member and moved inwardly by the coupler during the first part of the buffing action to compress said adjacent spring shock absorbing member, said friction shock absorbing mechanism being compressed by inward movement of the coupler during the latter part of the buffing action; and yoke acting means operatively connected to the coupler for compressing the spring shock absorbing member in back of the bolster in tandem with said friction shock absorbing mechanism, said yoke means being operatively connected with both of said spring shock absorbing members to actuate the same in tandem during draft movement of the coupler.
11. In a draft rigging for railway cars, the combination with a car underframe structure including fixed spaced draft sills, and a body bolster; of spring shock absorbing members in front and in back of said bolster; a coupler; a friction shock absorbing mechanism interposed between the coupling shank and the spring shock absorbing member in front of the bolster; and means operatively connected to the coupler for actuating both of said spring shock absorbing members in draft while said friction shock absorbing mechanism is idle, and actuating one only of said spring shock absorbing members in buff.
12. In a draft rigging for railway cars, the combination with fixed draft sills on the car; of a body bolster; spring members disposed in front and in back of the bolster; front and rear followers cooperating with each spring; means for holding the rear followers against rearward movement; a coupler; a friction shock absorbing mechanism interposed between the coupler shank and the front follower of the spring means disposed in front of the bolster; and means connecting the coupler with the rear followers of both of the spring members for actuating the same in draft to effect compression of both of said spring members in tandem and means on said connecting means engaging the front follower of the spring disposed in back of the bolster to actuate said follower and compress said spring in tandem with the friction shock absorbing mechanism during a buffing movement of the coupler.
13. In a draft rigging for railway cars, the combination with a pair of shock absorbing spring members; of a friction shock absorbing mechanism; means for actuating the friction shock absorbing mechanism in buff, one of said spring members being actuated

through the friction shock absorbing mechanism in advance of the latter in buff; and means connected to said actuating means for operating the spring members in tandem during a draft action without effecting operation of said friction shock absorbing mechanism and for operating one of said spring members in tandem with the friction shock absorbing mechanism in buff.

In witness that I claim the foregoing I have hereunto subscribed my name this 15th day of May, 1929.

JOHN F. O'CONNOR.
